(57) **CLAIM**

The ornamental design for lamp, as shown and described.

DESCRIPTION

FIG. 1 is a perspective view of a lamp showing a first embodiment of our new design;

FIG. 2 is a top plan view thereof;

FIG. 3 is a side elevational view from the right and left sides thereof;

FIG. 4 is a side elevational view from the front and rear thereof;

FIG. 5 is a bottom plan view thereof;

FIG. 6 is a perspective view of a lamp with an intelligent module showing a third embodiment of our new design;

FIG. 7 is a side elevational view from the right and left sides with an intelligent module thereof; and,

FIG. 8 is a perspective view thereof.

The broken lines in the figures represent unclaimed subject matter and form no part of the claimed design.
